UNITED STATES PATENT OFFICE.

JOHN T. HENDERSON, OF COUNCIL BLUFFS, IOWA.

DESIGN FOR A TOY.

SPECIFICATION forming part of Design No. 27,879, dated November 16, 1897.

Application filed September 28, 1897. Serial No. 654,182. Term of patent 3½ years.

To all whom it may concern:

Be it known that I, JOHN T. HENDERSON, a citizen of the United States, residing at Council Bluffs, in the county of Pottawattamie and 5 State of Iowa, have invented and produced a new and original Design for a Sounding Toy; and I do declare the following to be a full, clear, and exact description of the same, reference being had to the accompanying drawings, forming a part thereof.

In the accompanying drawings, Figure 1 shows a central sectional view of my new design for a sounding toy, while Fig. 2 is a top view thereof.

15 As is shown in the drawings, the leading features of my invention are, first, a central disk 1, surrounded by a concentric series of rings 4 4 4, which are of increased circumference, and between each of the rings 4 is a thin rib 20 5, these thinner ribs 5 and the rings 4 coming

in alternate series. I finally provide the flat rim 5, from which extends a semicircular bead 2, the whole being an integral part of any suitable material.

The surface of this toy may be either engraved, stamped, or colored, as desired, and it should be further understood that the device may be of any suitable size or material.

Having thus described my invention, what I claim as new, and desire to secure by Letters Patent, is—

The design for a sounding toy as herein shown and described.

In testimony whereof I affix my signature in presence of two witnesses.

JOHN T. HENDERSON.
